UNITED STATES PATENT OFFICE.

ALBERT VAN NESS, OF BELOIT, ASSIGNOR TO C. P. STEVENS, OF MITCHELL COUNTY, KANSAS.

WINDMILL.

SPECIFICATION forming part of Letters Patent No. 444,262, dated January 6, 1891.

Application filed November 12, 1887. Serial No. 254,964. (No model.)

To all whom it may concern:

Be it known that I, ALBERT VAN NESS, a citizen of the United States, residing at Beloit, in the county of Mitchell and State of Kansas, have invented certain new and useful Improvements in Windmills; and I do hereby declare the following to be a full, clear, and exact description of the invention, such as will enable others skilled in the art to which it appertains to make and use the same.

This invention relates to an improvement in windmills.

The object is to provide a simple and effective device by means of which the power of the wind may be exerted to elevate water from deep wells or cisterns.

The invention consists in a combination and arrangement of various novel features hereinafter fully described, and specifically designated in the claims.

In the accompanying drawings, in which like letters of reference indicate corresponding parts in all the figures, I have illustrated an embodiment of the invention, in which—

Figure 1 represents a side elevation of a windmill with my improvements applied. Fig. 2 represents a horizontal section of the same, the line of section being through the top of the tower. Fig. 3 represents a plan view of the tower and mast, showing the position of its vanes. Fig. 4 is a rear view of the clutch for throwing the drum into and out of operation. Fig. 5 is a detail view of the arrangement of levers for operating the clutch, and Fig. 6 is a detail view of the bucket and its automatic valve.

In the drawings an ordinary tower is shown, (designated by A,) the tops of the standards of which are secured together by means of a ring a, there being bolts passing through lugs a' upon the outer side of the ring and the upper end of each post. Upon a cross-beam a², near the top of the tower, is stepped a mast B by means of a plate a³, bolted to the cross-beam a² and having a seat formed in it for the reception of a lug formed on the bottom of a plate a⁴, secured to the lower end of the mast and being provided with a flanged outer edge to better adapt its rigid attachment thereto. To the bottom of the mast may also be secured a tube b, passing through the cen-

ter of the plates a³ and a⁴ and extending through and below the cross-beam a² and communicating with an opening b' in the lower end of the mast, which opening leads to one side of the mast, being designed for the passage of the rope or chain operating the bucket. Mounted in brackets at suitable points upon the sides of the mast are idlers b², bearing against the inner side of the ring a for the purpose of allowing the mast to turn freely, yet acting as braces to hold it in an upright position. To one side of the mast near the top is bolted a bracket b³, provided with a bearing b⁴ for the wheel-shaft C, to the outer end of which is attached a wind-wheel, which may be any form preferred. Upon the rear of the shaft is loosely mounted a drum D, to which is secured one end of the bucket-rope d, the rope being caused to be wound upon or unwound therefrom, and the bucket consequently operated by means of a clutch E, mounted upon the shaft at the inner end of the drum. The clutch consists of an arm e, rigidly mounted upon the shaft and rotating with it, one end of which arm is bent inward and overhangs a flange d' upon the drum, which forms a tread or surface for a strap e', of thin flexible metal, secured at one end to the overhanging portion of the arm e, its opposite end being attached to one end of a bent rod e², which also overhangs the flange d' of the drum, the movement of this end of the bent rod being limited by means of a guide-rod secured to the arm e, and by which means the lower portion of the arm e and the bent rod are held in close relation to each other. The opposite end of the bent rod e² carries a pin e³, which works vertically in a slot, an opening (shown in dotted lines) in a lug e⁴ extending laterally from the end of the arm e. The pin is secured near its lower end to a short bar e⁵, from which it extends upward, the ends of the bar being formed into trunnions e⁶, upon which are hung links e⁷, the opposite ends of the links being secured to a collar e⁸, mounted loosely and sliding upon the shaft C, by which arrangement when the collar e⁸ is moved laterally upon the shaft C toward the drum D the bent rod e², to which the band e' is attached, is drawn up and the band will be tightened upon the flange

and the drum caused to revolve with the shaft, and when the collar is moved in the opposite direction or away from the drum the band is slackened from upon the flange and 5 the drum permitted to revolve independently of the shaft.

It will be understood that when the sliding collar e^8 is in its normal position the band e' does not contact with the flange of the drum; 10 but when the collar is moved toward the drum it elevates the arm e^2 through the medium of the links e^1 and rod or pin c^3 , connected with the links and also with the arm e^2 , and as a consequence brings the lower inturned end 15 thereof in contact with the flange of the drum, causing the band to tighten against the drum and revolve the same with the shaft, and when the collar is moved away from the drum it depresses or lowers the 20 pin e^3 and bent rod e^2 , consequently disengaging the lower end of the rod from the flange of the drum; or, in other words, the movement of the collar e^8 toward the drum elevates the bent rod and brings the lower 25 end thereof in contact with the flange of the drum, and the movement of the collar from the drum lowers the bent rod and removes the lower end from engagement with the flange of the drum. The lateral movement of 30 the collar and the consequent engagement of the drum are accomplished automatically, and at the moment the bucket has reached its proper position, by means of a link e^9 , attached to the collar e^8 , the opposite end of the 35 fork being pivoted to a bar e^{10} , sliding in guides attached to the side of the bracket b^4 . To this bar is pivotally attached one end of a short link e^{11} , its opposite end being pivoted to a weighted lever e^{12} , one arm of which is 40 pivoted to the bracket, while the other arm engages one end of a rod e^{13} , extending downward and having an eye e^{14} formed upon its lower end, through which the bucket-rope passes. Upon the bucket-rope is secured a 45 stop e^{15} , placed at such point that when the bucket has been elevated to a sufficient height the stop will be brought into contact with the lower end of the rod e^{13} , raising the rod and throwing the weighted lever over in the opposite 50 direction, as shown in Fig. 5.

When the clutch is in gear, the links e^1 and pin e^3 are in line, and the clutch thus locked in position. When the lever e^{12} begins to rise, the stud e^{16} travels in the slot e^{17} in the 55 end of the rod e^{11} , and thus the weight on the lever passes its center of gravity before the collar begins to move upon the shaft C, the force of the falling lever then causing it to be moved immediately, and the drum, quickly 60 released by the clutch, is free to revolve in the opposite direction by the weight of the falling bucket. A similar stop is secured upon the rope at a certain point above the other, so that when the bucket has reached the 65 proper depth the stop will strike the eye upon the rod e^{13} , depressing the rod, which in turn causes the weighted lever to be drawn back

to its original position, the clutch being again thrown into gear with the drum and the rope again begins its ascent.

The bucket used is preferably cylindrical in shape and works in a tube placed within the well. Within this bucket F is a valve f , covering a lower compartment f' , provided with an opening for the inlet of water. To 75 this valve is attached a rod f^2 , its opposite end being attached to one end of a small trip-lever f^3 , pivoted near the top of the bucket.

Depending from one end of the beams of the tower at a convenient point is a rod f^4 , 80 carrying upon its lower end a disk f^5 , which encircles the rope and acts as a stop to trip the lever f^3 , and thus operate the valve to discharge the bucket. The upper end of the lever is curved outward, its opposite or lower 85 end occupying a position at the opposite side of the pivotal point to that occupied by the curved upper end, the lever being so shaped and placed for the purpose of allowing it to exert its greatest power at the moment its 90 upper end strikes the disk f^5 , when the greatest resistance is to be overcome in starting the valve.

The speed of the descending bucket is regulated by means of fans G, attached to the 95 rear of the drum, the resistance to the air acting as a brake when the drum is in rapid motion.

The vane II is hinged to the mast a suitable distance below the wheel-shaft and is 100 suitably braced thereon. A second vane h is rigidly secured and braced to the side of the mast perpendicular to the line of the vane II. The vane II is provided with a spring h' , secured to an arm extending from the 105 mast. By this arrangement the speed of the wheel may be controlled. When the force of the wind becomes too great, the vane h is thrown partially around, the spring h' allowing the large vane II to change its position 110 in relation to the mast, and the wheel thus brought around in a line with the vanes presenting less surface to the wind.

Having thus fully described my invention, what I claim as new, and desire to secure by 115 Letters Patent, is—

1. In a windmill, the combination, with the wheel-shaft, of a drum loosely mounted thereon for the operation of the bucket-rope, an arm mounted rigidly on the wheel-shaft, a 120 strap secured to one end of said arm and resting upon a flange formed upon the drum, the bent rod carrying a pin in one end, its opposite end carrying the opposite end of the strap, said pin engaging a lug on said arm, 125 and means whereby said pin is moved vertically in said lug, operating the bent rod, and causing the strap to bind upon or loosen from the flange on the drum, substantially as described.

2. In combination with a windmill, the clutch governing the revolution of the drum for operating the bucket-rope, said clutch comprising an arm rigidly mounted on a 130

wheel-shaft and carrying one end of the strap bearing on a flange on the drum, the bent rod having the strap attached at one end, the opposite end carrying the pin moving vertically through a lug on the arm, a collar mounted loosely on the wheel-shaft and sliding laterally thereon, links connecting said collar and the bent rod, and a lever operated by a bucket-rope and connected to the collar, whereby the collar will be moved laterally upon the wheel-shaft and the clutch be drawn into or out of engagement with the drum, substantially as described.

3. In a windmill, the combination, with the wheel-shaft, of a drum mounted loosely thereon, a clutch mounted rigidly thereon, a sliding rod mounted on the main frame and engaging a sliding collar on the main shaft, a weighted lever pivoted on the main frame, a

rod pivotally connecting said weighted lever to the sliding bar and having a slot in which the pivot on the weighted lever moves, a rod pivoted at one end to the weighted lever and at its opposite end having an eye through which the bucket-rope passes, and stops placed at given points upon said bucket-rope, all combined and arranged to operate for the purpose of throwing the drum into and out of operation with the wheel-shaft, and thus cause the winding and unwinding of the rope thereon, substantially as and for the purpose set forth.

In testimony whereof I affix my signature in presence of two witnesses.

ALBERT VAN NESS.
